UNITED STATES PATENT OFFICE.

RUSS J. CHRISTY, OF FREMONT, OHIO.

KNIFE.

SPECIFICATION forming part of Letters Patent No. 632,239, dated September 5, 1899.

Application filed December 17, 1898. Serial No. 699,590. (No model.)

To all whom it may concern:

Be it known that I, RUSS J. CHRISTY, a citizen of the United States, residing at Fremont, Sandusky county, State of Ohio, have invented 5 certain new and useful Improvements in Knives, of which the following is a specification.

My invention relates to paring-knives; and it consists of a knife formed from a thin flexible blade of steel, with a cutting edge at the side near one end and reinforced at the edges of the handle portion by reinforcing-ribs, as fully set forth hereinafter, and illustrated in the accompanying drawings, in which—

15 Figure 1 shows in perspective the form of the strip from which the blank is made. Fig. 2 is the blank before sharpening. Fig. 3 is a blank after sharpening. Fig. 4 is a perspective view of the finished knife. Fig. 5 is a 20 perspective view of a reinforcing-rib; and Fig. 6 is a cross-section on the line 6 6, Fig. 4.

In constructing my improved paring-knife I first take a sheet or plate of thin flexible steel and cut therefrom a strip with straight 25 side edges and preferably of uniform width, forming a blank A. Preferably the blank is punched at one end and sheared off or beveled at one side, near the other end, forming an inclined edge x, Fig. 2. The blank is then 30 tempered and ground off toward the edge x, or otherwise sharpened to form the cutting edge, Fig. 3, the short portion thus sharpened at one side forming the cutting portion of the knife-blade, while the longer part, in 35 one piece with the cutting portion, constitutes the handle portion of the blade. Inasmuch, however, as the blade is of extreme thinness I reinforce the handle portion and also the cutting part, if desired, by reinforcing-strips a a, each consisting of a grooved 40 rib formed of a piece independent of the material of the blade and applied to the straight edge, as shown in Fig. 5. By thus constructing the knife I am enabled to use extremely 45 thin stock, which not only reduces expense while permitting the use of the best quality of steel, and also enabling the strips to be readily and uniformly tempered, thereby securing blades which will be flexible, yet of 50 such temper as to keep their cutting edges.

The handle being in one piece with the blade avoids riveting and expensive manipulation, while the reinforcing-ribs prevent injury to the hands from the sharp edges of the handle portion and impart rigidity to the handle 55 portion which is essential in consequence of the thinness of the blade. In other words, by the use of the reinforcing-ribs on the handle portion of a blade having the cutting and handle portion in one piece I am enabled to 60 use stock material much finer in quality and much thinner and less expensive, and more easily manipulated and tempered than would otherwise be the case. When greater rigidity is desired in the cutting portion of the 65 blade, the back rib a may extend for any desired extent along the back of the cutting portion of the blade. The cutting edge may be in line with the front edge of the blade, or at an angle, as shown, or straight or curved. 70 A preferable rib construction consists in forming each rib of a narrow strip of sheet iron, steel, zinc, or other metal bent to a U shape transversely, as shown in Fig. 5, and then applied to the blade and swaged. The edge 75 strips may be retained in position by swaging or by applying them to the blade and then japanning or galvanizing the handle portion or coating it by dipping in molten tin, zinc, or other material or composition. 80

By forming the handle part of the blade with straight edges I can shear it from the plate without the use of dies, thus greatly reducing the cost of construction, and by using straight reinforcing-strips I further reduce 85 the cost of construction, while securing a form of article more serviceable for its intended purpose than constructions heretofore devised.

Without limiting myself to the precise construction shown, I claim as my invention—

1. A paring-knife consisting of a thin flexible blade A having in one piece a handle portion with straight side edges and a cutting portion with a sharpened edge, and independent reinforcing-ribs fixedly secured at the edges of the handle portion, substantially as described. 95

2. A paring-knife consisting of a thin flexible metallic blade having a short cutting por- 100

tion sharpened at one edge, and a longer handle portion, in one piece with the cutting portion with straight edges, and with independent grooved reinforcing-strips *aa*, secured fixedly to said edges, the back strip extending also along the rear edge of the cutting portion, substantially as described.

In testimony whereof I have signed my name to this specification in the presence of two subscribing witnesses.

RUSS J. CHRISTY.
